SAFETY RAZOR

Charles F. Henley, London, England, assignor to
Ever-Ready Razor Products Limited, London,
England, a British company

Application September 14, 1951, Serial No. 246,559

Claims priority, application Great Britain
September 18, 1950

1 Claim. (Cl. 30—70)

1

This invention relates to safety razors adapted to hold centrally-slotted double-edge blades. The invention has particular reference to a safety razor of the kind in which the blade is clamped down on to a guard by means of a sectional clamping cover, the guard surmounting a handle.

The object of this invention is to provide an improved safety razor of this kind.

The foregoing and other objects of the invention will be more readily understood from the following description of a preferred embodiment which is illustrated, by way of example, in the accompanying drawings, wherein:

Figure 1 is a side view, partly in section, of one construction of razor according to this invention, showing the blade clamping means closed.

Figure 2 is a plan view of Figure 1.

Figure 3 is an end view, partly in section, the section being taken on line III—III of Figure 1.

Figure 4 is a cross section on line IV—IV of Figure 1.

Figure 5 is a plan view showing the blade clamping means open.

Figure 6 is a cross section on line VI—VI of Figure 5.

Figure 7 is a pictorial view of one of the blade clamping members and the associated operating element, and

Figure 8 shows a typical narrow slotted blade for use with the razor shown in Figures 1 to 7.

The safety razor illustrated in Figures 1 to 7 of the drawings is provided with twin clamping elements which are so thin that when arranged in the opened position they can pass through the narrow central slot provided in several brands of double-edge blades at present marketed. The razor comprises a tubular handle 1 having the customary knurled or roughened grip portion 2 and a stepped bore consisting of a large diameter bore portion 3 and a co-axial small diameter bore portion 4.

Within the bore portion 3 is snugly received, with freedom to rotate, the barrel 5 of a nut element 6, one end of the nut barrel 5 having a central drilled and tapped socket 7 for screw-threaded engagement with the male threaded end portion 8 of the shank 9 of a substantially T-shaped element 10. The outer end of the nut element 6 is made in the form of a knurled or roughened finger gripping knob 11, a rim 12 on said knob 11 being rolled in after assembly to enter an annular groove 13 in the grip 2 of the handle 1, thereby preventing withdrawal from the handle bore portion 3 of the nut element 6.

2

whilst permitting of free rotation of said nut element 6.

The handle 1 is surmounted by a fixed head 14 consisting of a stepped channel member 15 and a substantially rectangular top plate 16 having its opposite longitudinal edge portions 17 constituting a symmetrical guard of generally known form and provided with comb-like teeth or, as shown, with slots 18 parallel to the side edges of the guard. The T-shaped element 10 forms part of a blade clamp operating means, other essential parts being the manually operable nut 6 and the twin clamping members 19. These clamping members 19 are of identical symmetrical form so that any two members can be paired for use together. Each clamping member 19 is in the form of a metal plate bent or doubled over to approximately an L shape in cross section, that is, a short limb 20 and a long limb 21 meeting at a generously-radiused junction edge 22. The short limb 20 is provided with a pair of notches 23, symmetrical in relation to the length of the clamping member 19 and to a semi-circular opening 24 provided at the middle of the clamping member 19 at the junction edge 22. The opening 24 breaks into a groove 25 formed in the middle of the limb 20 in such a manner as to provide adjacent the rear face 26 of said limb a pair of longitudinally spaced ledges 27. The aligned grooves 25 of a pair of clamping members 19 when disposed in back-to-back contact, as shown in Figure 3, provide a passage for the stem 28 of a pin 29 mounted in the upper end of the shank 9 of the T-shaped operating element 10, so as to constitute an axial extension of said shank 9. The pin 29 has a flat disc-like head 30 adapted to be accommodated in the aligned openings 24 of a pair of clamping members 19, said head 30 co-acting with the two pairs of ledges 27 of the two members 19. The cross bar 31 of the T-shape operating element 10 has upturned lugs 32 which are each wide enough to engage one aligned pair of notches 23 in the back-to-back clamping member limbs 20. It will be noted that the notches 23 are spaced from the middle grooves 25 of the clamping members 19 at such equal distances therefrom that the lugs 32 of the operating element 10 can pass through cross openings 33 which intersect the longitudinally contoured-edge central slot 34 of a double edge wafer blade 35. It will be noted that the blade 35 has a central opening 36 adapted to afford clearance for the disc head 30 of the pin 29 of the operating element 10 and is also provided with paired set-back end portions 37.

to engage angular location projections 38 formed at opposite ends of the top plate 16 of the razor head 14. The parts of this razor which co-operate with the blade slot 34 and openings 33 and 36 are of such dimensions, disposition and form as to enable the razor to receive interchangeably any one of a number of blades intended for use with a variety of different existing razors.

The top plate 16 of the razor head 14 has a central longitudinal slot 39 with a central enlargement 40 and a pair of symmetrical enlargements 41 for the passage therethrough of the clamping members 19 and the pin 29 and lugs 32 of operating element 10 respectively, and the limbs 20 of the clamping members 19 have end projections 42 adapted to engage under the top plate 16 adjacent the ends of slot 39 to limit the bodily upward movement of the clamping members 19.

For the purpose of mounting a blade 35 on the razor the nut 6 is turned by means of the knob 11 to cause the screwed portion 8 of the shank 9 of the clamp operating element 10 to screw into the socket 7 of said nut 6. This has the effect of causing the disc-head 30 of the pin 29 of element 10 to bear down upon the ledges 21 of the closed clamping members 19, with the result that the members 19 are rocked about the radiused edges 22 to bring the long limbs 21 thereof substantially erect and face to face, the short limbs 20 then extending outwards in opposite directions within the upper part of the channel 15 of the head 14. The blade 35 can then be placed on the razor top plate 16 with the erected limbs 21 of the clamping members 19 extending up through the blade slot 34. Reverse rotation of the nut 6 then elevates the operating element 10 to cause the lugs 32 to tilt the clamping members 19 in the opposite direction, so as to clamp the blade 35 on to the top plate 16 by the long limbs of said member 19.

To allow for manufacturing tolerances in the various components of the razor and for slight inaccuracies in assembly the upper part 9A of the shank 9 of the operating element 10 is made separate from the lower part 9B and the two parts are hingedly connected by a cross pin 43, so that the clamping members 19 carried by said upper part 9A are self-adjusting in the act of clamping the blade in position.

I claim:

A safety razor comprising a tubular handle; a head surmounting said handle and consisting of a channel member communicating with the handle interior and of a longitudinally slotted top plate having laterally extending portions forming a symmetrical guard; blade clamping means in the form of twin covers constituted by plates of L-shape in cross section with rounded edges at the junctions between long and short limbs of the L-sectioned cover plates, said cover plates being normally disposed in a blade clamping position with the long limbs of the cover plates extending outwards to overlie said guard and with the short limbs thereof back to back and symmetrical to the longitudinal axis of the handle and the head with its guard plate, said short limbs being fashioned to define therebetween a central passage, aligned notches on opposite sides of said central passage and projections extending from the ends of said limbs for engaging the under side of said top plate; and a blade clamp operating mechanism comprising a sleeve-like nut mounted for rotation within the handle interior and held against axial movement, with the lower end of said nut accessible for finger gripping, an axially displaceable push-pull member having a T-shaped head accommodated in the channel member of said head and having a screwed shank making threaded engagement with said nut, the arms of the T head terminating in uprights each for engaging said aligned notches in the short limbs of the cover plates to hold the cover plates in blade clamping positions and having an extension of said shank for passing through the central passage defined between said short limbs and shaped for engaging the upper sides of the cover plates.
